CLAIM

The ornamental design for a beverage container lid, as shown and described.

DESCRIPTION

FIG. 1 is a top right rear perspective view of a first embodiment of a beverage container lid, showing my new design in condition of use;

FIG. 2 is a bottom left front perspective view thereof.

FIG. 3 is a rear elevational view thereof.

FIG. 4 is a front elevational view thereof.

FIG. 5 is a left elevational view thereof.

FIG. 6 is a right elevational view thereof.

FIG. 7 is a top plan view thereof.

FIG. 8 is a bottom plan view thereof.

FIG. 9 is a top right rear perspective view thereof, in a first alternate configuration of use;

FIG. 10 is a top right rear perspective view thereof, in a second alternate configuration of use;

FIG. 11 is a top right rear perspective view of a second embodiment of a beverage container lid, showing my new design in condition of use;

FIG. 12 is a bottom left front perspective view thereof.

FIG. 13 is a rear elevational view thereof.

FIG. 14 is a front elevational view thereof.

FIG. 15 is a left elevational view thereof.

FIG. 16 is a right elevational view thereof.

FIG. 17 is a top plan view thereof.

FIG. 18 is a bottom plan view thereof.

FIG. 19 is a top right rear perspective view thereof, in a first alternate configuration of use; and,

FIG. 20 is a top right rear perspective view thereof, in a second alternate configuration of use.

The broken lines shown in the drawings depict portions of the beverage container lid that form no part of the claimed design.

The shading lines shown in the drawings represent the three-dimensional contour of the claimed design and are not intended to indicate surface decoration.
